[57] **CLAIM**

The ornamental design for a combined front and rear fenders, chain guard, engine cover and fuel tank for a moped, as shown and described.

DESCRIPTION

FIG. 1 is a perspective view of the combined front and rear fenders, chain guard, engine cover and fuel tank for a moped showing my new design, the broken lines being for illustrative purposes only;

FIG. 2 is a top plan view thereof;

FIG. 3 is a side elevational view thereof opposite to that shown in FIG. 1;

FIG. 4 is a front elevational view thereof;

FIG. 5 is a rear elevational view thereof; and

FIG. 6 is a bottom plan view thereof.

FIG. I
